UNITED STATES PATENT OFFICE.

PERCY M. ELLIOTT, OF CHICAGO, ILLINOIS.

SHEET-METAL FREIGHT-CAR DOOR.

1,300,143.

Specification of Letters Patent.

Patented Apr. 8, 1919.

Application filed May 8, 1915. Serial No. 26,768.

To all whom it may concern:

Be it known that I, PERCY M. ELLIOTT, a citizen of the United States, residing at Chicago, in the county of Cook and State of Illinois, have invented certain new and useful Improvements in Sheet-Metal Freight Car Doors, of which the following is a specification.

My invention relates in general to freight car doors, and more particularly to an improved reinforced sheet metal car door. The sliding doors of freight cars are, owing to their exposed positions at the sides of the cars, subjected to a great deal of wear and tear, and when made entirely of wood must be quite heavy in order to possess the requisite strength, and even then they are frequently injured through contact with adjacent objects. The use of metal as the material for freight car doors is open to the objections that the doors are rendered extremely heavy if made sufficiently strong, while if so constructed as to be reasonably light they are liable to be distorted when subjected to the inevitable rough usage.

The primary object of my invention is to provide an all-metal freight car door which will be light in weight, and at the same time possess adequate structural strength.

A further object of my invention is to provide a sheet metal door for freight cars which will be so reinforced by pressed sheet metal bars as to possess the requisite strength without being rendered heavier than the usual freight car door.

A still further object of my invention is to provide a reinforced sheet metal freight car door, in which the reinforcements will not only strengthen the door vertically and horizontally, but will also co-operate with the edges of the sheet metal to provide strong peripheral-guiding and weather-proofing flanges.

A still further object of my invention is to provide an all-metal car door which will be simple in construction, inexpensive in manufacture, and durable in use.

My invention will be more fully disclosed hereinafter with reference to the accompanying drawings, in which the same is illustrated as embodied in several practical and efficient forms, and, in which:

Figure 1 is a front elevational view of a freight car door embodying my invention;

Fig. 2 is a view similar to Fig. 1, showing a modification, in which the reinforcing bars

are on the inner surface, instead of on the outer surface, of the door;

Fig. 3 is an enlarged vertical section on the line 3—3 of Fig. 1, the central portion 60 of the door being broken away;

Fig. 4 is a view similar to Fig. 3, taken on the line 4—4 of Fig. 2;

Fig. 5 is a view similar to Fig. 4, showing a modification of the structure of the top 65 portion of the door to which the hangers are secured;

Fig. 6 is a horizontal sectional view on the line 6—6 of Fig. 1;

Fig. 7 is a similar view on the line 7—7—70 of Fig. 2;

Fig. 8 is an enlarged detail elevation showing the intersection of the central, vertical and horizontal reinforcing bars; and

Fig. 9 is a view similar to Fig. 8, showing a modification of the reinforcing bar which overlies the other, which is pressed into proper shape without having any portion thereof cut away.

Similar reference characters are used in 80 the several figures of the drawings to designate similar parts.

Referring particularly to the form of my invention illustrated in Figs. 1, 3 and 6, reference letters A and B designate two sections of sheet metal, having their adjacent vertical edges overlapped, as shown by the reference characters *a* and *b* in Fig. 6. The two sections A and B are together of the desired size of the freight car door, and together form a covering for closing the door opening when the door is in proper closed position relatively thereto. While I have shown only two sections of sheet metal, I do not desire to be limited thereto, as the door covering may be made in more sections having their adjacent edges overlapped and secured together.

Reference letters C, D and E designate horizontal reinforcing bars extending across 100 the sections A and B, the bar C being located adjacent the top of the door, the bar D centrally of the door, and the bar E adjacent the bottom of the door.

Each of the said horizontal reinforcing 105 bars is formed of pressed sheet metal, and comprises a central web spaced away from the adjacent surface of the sections A and B of the sheet metal door covering, and oppositely projecting flanges which overlie and are riveted to the sheet metal covering.

Reference letters F, G and H indicate ver-

tical reinforcing bars made of sheet metal pressed into the desired cross-section, which is preferably the same as the horizontally disposed reinforcing bars. The vertical bar

- 5 F is located adjacent the front of the door, while the vertical reinforcing bar G is located centrally, and the bar H adjacent the rear edge of the door.

The centrally located vertical and horizontal reinforcing bars D and G extend across each other at their point of intersection, such crossing being permitted either by cutting away portions of the flanges of the bar which extends over the other, as shown in Fig. 8, or by pressing the side flanges over the overlying bar outwardly into the same plane as the web thereof, as shown in Fig. 9, so that the bar will not be weakened by having portions thereof cut away. The 20 ends of the central vertical and horizontal reinforcing bars are joined to the corresponding reinforcing bars, which are located adjacent the edges of the door, in any suitable manner. The intersecting ends of the 25 top and bottom, and front and rear reinforcing bars are also overlapped and tightly secured together, and also to the sheet metal door covering.

By referring to Fig. 3 it will be seen that 30 the reinforcing bar E, located adjacent the bottom of the door, is provided with a depending flange e which closely engages and is tightly riveted to the lower portion of the sheet metal covering of the door, so as to 35 form a reinforced projection along the bottom of the door to engage the usual bottom door guide brackets L secured to the car side below the plane of the door opening. By reference to the same figure it will be 40 seen that the top reinforcing bar C is provided with an upwardly projecting flange c, which closely engages the top portion of the sheet metal door covering, and is riveted thereto to form a strong flange at the top of 45 the door to which hangers I are secured.

Each hanger I is preferably formed with an offset portion K, of a contour to conform with the cross-section of the top reinforcing bar around which it extends, the same rivets 50 which secure the reinforcing bar to the sheet metal covering also preferably passing through and securing the hanger to the top of the door. The hanger is provided with a roller i, which rests upon a suitable track J 55 secured to the side of the car above the plane of the door opening. The track J may be of any suitable construction, such, for instance, as a channel beam provided with a depending flange j extending between inner 60 and outer guiding portions of the hanger I.

By reference to Fig. 6 it will be seen that the front reinforcing bar F is provided with a forwardly projecting flange f, which closely engages and is riveted to the front 65 portion of the sheet metal door covering,

thereby forming a reinforced flange at the front of the door to engage the door post M when the door is closed. The door post M is preferably provided with a flange m between which and the door jamb P the reinforced 70 front portion of the door extends when the door is closed, as shown in Fig. 6. By reference to the same figure, it will be seen that the vertical reinforcing bar H, located adjacent the rear edge of the door, is provided 75 with a flange h closely engaging and riveted to the sheet metal door covering, and also with a rearwardly and inwardly projecting flange N, which forms a weather-strip on the door to engage a weather-strip o formed 80 on the rear post O. When the door is closed, the weather-strip N on the door closely engages the weather-strip o at the rear of the door opening, so as to prevent the passage 85 of foreign matter between the rear edge of the door and the rear door post when the door is closed.

In Figs. 2, 4 and 7 I have illustrated a modified form of my invention, in which the reinforcing bars are located on the inner 90 surface of the sheet metal door opening, so that the outer surface of the door presents a smooth surface, whereas in the form of my invention above described the reinforcing bars are located on the outer surface of the sheet metal door opening, so that the smooth 95 surface is on the inside of the car. In Figs. 2, 4 and 7 reference characters A' and B' indicate sections of sheet metal which form the door covering, and which are overlapped 100 at the vertical center of the door, as shown in Fig. 7. While in this modified form of my invention the sheet metal door covering is shown as formed in two vertical sections, yet it will be understood that the sheet metal 105 door covering may be formed in more or less sections overlapped and tightly secured together at their adjoining edges.

Reference characters C', D' and E' designate the horizontal reinforcing beams located respectively at the top, center and bottom of the door, while reference characters F', G' and H' indicate the vertical reinforcing bars located respectively at the front, center and rear of the sheet metal door covering. The top reinforcing bar C' is so bent as to have a Z-shaped cross-section conforming to the cross-section of the sheet metal door covering at the top thereof, as 110 shown in Fig. 4. The door hanger I' conforms to the contour of the reinforced top portion of the door, and is riveted thereto, preferably by the same rivets as secure the top reinforcing bar to the sheet metal door covering.

The lower horizontal reinforcing bar E' is also so bent as to have a Z-shaped cross-section along its lower edge to conform to a similar contour imparted to the bottom of the sheet metal door covering, so as to form 115 120 125 130

a reinforced bottom flange e' lying in a vertical plane inside of the outer surface of the door, to engage the usual bottom door guide brackets L .

- 5 By referring to Fig. 7 it will be seen that the front vertical reinforcing bar F' is so bent as to have a Z-shaped cross-section along its front edge to closely engage and conform to a similar contour of the front portion of the sheet metal door covering, thereby forming a reinforced flange f' along the front of the door to engage the flange m on the door post and the door jamb P . The weather-strip at the rear of the door is 15 formed by bending rearwardly and inwardly the sheet metal reinforcing bar H' , as indicated at N' , which is adapted to coöperate with the weather-strip o on the door post O at the rear of the door opening. The rear 20 vertical reinforcing bar H' is also provided with an inwardly projecting flange h' , to reinforce the overlying inwardly projecting portion of the sheet metal door covering.

In Fig. 5 I have shown a slight modification 25 in the cross-section of the top of the door, and in the contour of the hangers secured thereto. In said figure the top horizontal reinforcing bar C^2 is not only provided with an upwardly projecting vertical 30 flange which closely engages the sheet metal door covering, but is also provided with an inwardly projecting horizontal flange c^2 which underlies the corresponding flange formed along the top of the sheet metal door covering. The door hanger R^2 , in this modification of my invention, merely engages the 35 vertical outer surface of the door, and is not provided with offset portions to extend inwardly with respect to the outer surface of 40 the door, as is the case with the door hangers shown in Figs. 3 and 4.

From the foregoing description it will be observed that I have invented an improved sheet metal freight car door comprising a 45 sheet metal plate covering and vertical and horizontal intersecting reinforcing bars, which not only serve to contribute the necessary rigidity to the door, but also coöperate with the peripheral portions of the sheet 50 metal covering in forming reinforced flanges for guiding and supporting the door, and in forming weather-proof joints through engagement with the plane around the door opening, when the door is closed. It will be 55 further observed that the reinforcing bars extend continuously across each other at their points of intersection, and are so fashioned as to all lie in the same vertical plane either on the outside, as shown in Figs. 1, 3 60 and 6, or on the inside, as shown in Figs. 2, 4 and 7, of the sheet metal door covering.

I claim:—

1. A freight car door comprising a sheet metal covering, and a plurality of vertical

and horizontal intersecting reinforcing bars 65 formed of pressed sheet metal and comprising central web portions spaced away from the covering and extending across each other at their points of intersection and side flanges overlying and secured to said covering. 70

2. A freight car door comprising a sheet metal covering, and vertical and horizontal reinforcing bars formed of pressed sheet metal and comprising central web portions 75 spaced away from the covering and side flanges overlying and secured to said covering adjacent the edges thereof, the ends of said vertical and horizontal bars overlapping each other and being secured to the corners 80 of said covering.

3. A freight car door comprising a sheet metal covering, vertical and horizontal reinforcing bars formed of pressed sheet metal and comprising central web portions spaced away from the covering and side flanges overlying and secured to said covering adjacent the edges thereof, and intermediate vertical and horizontal reinforcing bars also comprising side flanges secured to said covering and central web portions spaced away 85 from the covering and extending across each other and lapping at their ends the central web portions of the reinforcing bars adjacent the edges of said covering. 90

4. A freight car door comprising a sheet metal covering formed of a plurality of sections overlapped and secured together at their adjoining edges, reinforcing bars comprising central web portions spaced away 100 from the covering and side flanges secured to said covering adjacent the edges thereof, and a reinforcing bar also comprising a central web portion spaced away from the covering and side flanges overlying and secured to the overlapped portions of the sections of 105 said sheet metal covering and having the ends of its central web portion overlying and secured to the web portions of the adjacent edge reinforcing bars. 110

5. A freight car door comprising a sheet metal covering, and a plurality of continuous reinforcing bars secured to said covering, the said reinforcing bars each comprising a central web portion spaced away from the covering and secured directly to the central web portions of other bars at intersecting points and side flanges overlying and secured to the said covering. 115

6. A freight car door comprising a sheet metal covering, an inwardly projecting flange on said covering around the edges of the door integral therewith, and reinforcing bars formed of pressed sheet metal secured to the inner surface of said covering adjacent the edges thereof, the said reinforcing bars having inwardly projecting flanges at their outer edges underlying and reinforce. 120 125

ing said inwardly projecting flanges on the sheet metal covering around the edges of the door.

7. A freight car door comprising a sheet metal covering, vertical and horizontal reinforcing bars formed of pressed sheet metal and secured to the inner surface of said covering adjacent the edges thereof, intermediate vertical and horizontal reinforcing bars secured to the inner surface of said covering extending across each other and lapping at their ends the reinforcing bars adjacent the edges of said covering, the said reinforcing bars adjacent the edges of the

covering having flanges at their outer edges extending inwardly a distance corresponding to the distance said reinforcing bars project inwardly from the inner surface of said covering, and flanges on said covering at its outer edge overlying and reinforced by the 20 said flanges of the reinforcing bars.

In testimony whereof I have subscribed my name.

PERCY M. ELLIOTT.
